UNITED STATES PATENT OFFICE.

DANIEL HOGAN, OF NEW YORK, N. Y., ASSIGNOR TO THE MEINECKE & COMPANY, OF SAME PLACE.

DESIGN FOR A BED-PAN.

SPECIFICATION forming part of Design No. 34,042, dated February 5, 1901.

Application filed December 7, 1900. Serial No. 39,101. Term of patent 14 years.

To all whom it may concern:

Be it known that I, DANIEL HOGAN, a citizen of the United States, residing in the borough of Manhattan, New York city, in the county and State of New York, have invented and produced a new and original Design for a Bed-Pan, of which the following is a specification.

This design consists of a hollow bed-pan having a substantially oval-shaped opening in the top thereof and an elongated hollow handle, substantially elliptical in contour.

The design is illustrated in the annexed drawings, in which—

Figure 1 is a plan view of my new and novel design for a bed-pan. Fig. 2 is a side elevation thereof. Fig. 3 is a front elevation.

Referring to the drawings, *a* denotes the

hollow bed-pan, having a substantially oval-shaped opening in the top, as at *a'*, and the head, as at *a²*, thereof. The pan at its head is formed with an elongated curvilinear hollow handle *b*, substantially elliptical in contour.

The design gives a striking and characteristic appearance.

What I claim as new, and desire to secure by Letters Patent, is—

The design for a bed-pan substantially as shown and described.

In testimony whereof I have hereunto set my hand in the presence of two subscribing witnesses.

DANIEL HOGAN.
